S. GALERKIN.

EXTENSION TABLE SLIDE.

APPLICATION FILED MAY 26, 1919.

1,396,036.

Patented Nov. 8, 1921.

UNITED STATES PATENT OFFICE.

SAMUEL GALERKIN, OF MILWAUKEE, WISCONSIN.

EXTENSION-TABLE SLIDE.

1,396,036.

Specification of Letters Patent.

Patented Nov. 8, 1921.

Application filed May 26, 1919. Serial No. 299,932.

To all whom it may concern:

Be it known that I, SAMUEL GALERKIN, a citizen of Russia, residing at Milwaukee, in the county of Milwaukee and State of Wisconsin, have invented certain new and useful Improvements in Extension-Table Slides, of which the following is a specification, reference being had to the accompanying drawing, forming a part thereof.

10 This invention relates more particularly to slides for extension tables provided with equalizing devices, whereby movement of either end section of a table outward or inward, causes simultaneous and equal movement of the other end section in the opposite direction.

The main objects of the present invention are to increase the extensibility of the slides and hence of the tables to which they are applied without correspondingly increasing the length of the slide bars, in connection with means for causing simultaneous and equal extension and contraction of the slides at both ends; to avoid sagging and binding of the slide bars and provide a firm and stable support for both ends of a table when extended, particularly a table having a central leg or pedestal; to facilitate opening or extending and closing or contracting such tables; and generally to improve the construction and operation of extension tables.

It consists in the construction, arrangement and combination of parts as hereinabove particularly described and pointed out in the claims.

In the accompanying drawing like characters designate the same parts in the several figures.

40 Figure 1 is an inverted plan view of a closed extension table top provided with slides embodying the invention, and having a central pedestal or support which is shown in cross section, one end of the cap or cross piece of the pedestal being broken away to disclose the superposed slide; Fig. 2 is a fragmentary view of the table showing one of the slides partially extended; Fig. 3 is an enlarged central cross section on the line 3—3, Fig. 1, of one of the slides; and Figs. 4 and 5 are detail views of a portion of a slide bar and a flanged roller for connecting it with an adjoining bar, Fig. 4 being a side elevation, parts being broken

away and Fig. 5 a cross section on the line 55 5—5, Fig. 4.

In accordance with the invention, each slide comprises an uneven number, five or more, bars, a relatively fixed or stationary middle bar 1, two relatively movable or floating end or outside bars 2, and two or more, in the present case two, floating or relatively movable intermediate bars 3. The middle bars 1 are mounted on and fastened parallel with each other to the cap or cross piece 4 of a pedestal or central support 5. The corresponding end or outside bars 2, are fastened to the under side of the top sections 6 and 7 of the table. The intermediate sections 3 are provided in recesses in the under sides thereof, with oppositely and inwardly facing parallel longitudinal racks 10, extending from the middle portions of the bars to or toward their opposite ends. In a corresponding recess in the under side of each middle bar 1, is rotatably mounted a gear or pinion 11, meshing on opposite sides with the racks 10 of the adjoining intermediate bars 3.

Each middle bar 1 is provided with two oppositely or outwardly facing parallel longitudinal racks 14, extending from the middle portion thereof to or toward its ends, and the end or outside bars 2 are provided with oppositely or inwardly facing parallel longitudinal racks 15 in the same horizontal plane with the racks 14, and extending from the middle portions of the bars to or toward opposite ends thereof. Gears or pinions 17, of the same size and having the same number of teeth as the gears 11, are centrally and rotatably mounted on the intermediate floating bars 3, each meshing on opposite sides thereof with one of the racks 14 of the associated middle bar 1, and with the rack 15 of the adjoining end or outside bar 2.

As shown in Fig. 3, the racks 10 and gear 11 of each slide set in recesses in the bars 1 and 3, are in a plane above and parallel with the plane of the racks 14 and 15 and gear 17, set in shallower recesses in the bars 1, 2 and 3. The several gears may be rotatably connected with the bars on which they are mounted by round or oval headed wood screws 20, and the racks with which the gears mesh may be fastened to the bars by countersunk flat headed wood screws 21, as indicated by dotted lines in Fig. 3. The re-

cess in which the gear 11 of each middle bar is mounted may be bridged by a metal plate 24, fastened at the ends to the bar so as to confine the gear in place in case its pivot 5 screw becomes loose.

The several bars of each slide may be connected with and supported and guided on one another by the usual or any suitable means.

10 As shown in Figs. 3, 4 and 5, the bars are formed in their adjoining faces with registering longitudinal T-grooves, and each bar is provided adjacent one end thereof, with a block 26, fitted and fastened in its 15 T-groove and projecting therefrom into the groove of the adjoining bar.

In a recess formed in the protruding portion or tongue of each block 26, is rotatably mounted on a pin or screw 27, a flanged 20 roller 28. The flange of the roller working in the wider part of the groove in the adjoining bar, holds the adjoining bars together 25 face to face, and the periphery of the roller extending above and below the tongue or protruding portion of the block 26, facilitates the operation of the slides, each bar being connected with an adjoining bar by two rollers which carry the load to which the bars are subjected.

30 Each outside bar 2, is formed or provided on the upper side of the end which is attached to a table top section, with a raised seat or shim 30, as shown in Fig. 3, to prevent the relatively movable bars associated therewith from binding against the top sections of the table when it is being extended or closed. In like manner, the middle bars 1 are formed or provided on the under side with bearings or shims 31, which extend 35 below the lower sides of the associated floating bars and bear on the upper side of the cap or cross piece 4 of the pedestal, so as to prevent the floating bars from rubbing and binding against the cap or cross piece 40 when the table is extended or closed.

45 The blocks 26 serve as stops to limit the outward movement of the bars in extending the slides, and prevent the withdrawal of the racks from engagement with the gears 50 with which they co-operate. The inward or closing movement of the bars is limited by the engagement of stop pins 33, which are inserted in and project laterally from all but one of the bars, as shown in Fig. 2, and 55 engage with notches in the ends of adjoining bars, as indicated by dotted lines in Fig. 1, when the ends of the several bars are brought into alignment with one another and the top sections 6 and 7 of the table are 60 brought together.

65 In the operation of the slides, when either top section 6 or 7 of the table is drawn out or pushed in, the other section will be moved simultaneously to the same extent by the interaction of the gears and racks, the gears

11 engaging with the racks 10 compelling like and simultaneous movement of the bars 3 in opposite directions, and the gears 17 moving with the bars 3 in engagement with the racks 14 and 15 compelling like and 70 simultaneous movement in opposite directions of the bars 2, relative to the bars 3, so that a person at either end of the table is enabled to easily open or extend and to close or contract the table, without aid.

75 By the employment of five or more bars in each slide, connected with one another as hereinbefore described, a greater degree of extension is obtained, and when the slides are drawn out to the limit of their extension, 80 they overlap one another, and the rollers 28 between adjoining bars are separated sufficiently to prevent the floating bars from sagging at the ends of the slides and to afford a firm, stable support for the top 85 sections 6 and 7 of the table.

Various modifications in the details of construction and arrangement of parts of the slides may be made without departure 90 from the principle and scope of the invention as defined in the following claims.

I claim:

1. In an extension table the combination of a relatively fixed middle bar, floating end bars and floating intermediate bars slidably connected with one another side by side, two oppositely facing longitudinal racks fixed on the middle bar and extending in opposite directions from the central portion thereof, longitudinal racks mounted on the 100 intermediate and end bars, a gear mounted on the middle bar and meshing on opposite sides with racks on intermediate bars, and a gear mounted on each intermediate bar next to the middle bar and meshing on opposite sides with racks on the middle bar and the next outer bar.

2. In an extension table slide the combination of a relatively fixed middle bar provided with two oppositely facing longitudinal racks, oppositely movable end and intermediate bars slidably connected with one another and with the middle bar on opposite sides thereof and each provided with a longitudinal rack, a gear mounted on the middle 115 bar and meshing on opposite sides with the racks on adjoining intermediate bars, and gears mounted on the intermediate bars adjoining the middle bar in a plane below and parallel with that of the gear on the middle 120 bar, and each meshing on opposite sides with a rack on the middle bar and the rack on the adjoining outer bar.

3. In an extension table slide the combination of a relatively stationary middle bar 125 provided with oppositely facing longitudinal racks, longitudinally movable end and intermediate bars slidably connected with opposite sides of the middle bar and with one another and each provided with a longi- 130

- tudinal rack, a gear mounted on the middle bar and meshing on opposite sides with the racks of adjoining intermediate bars, and gears mounted on the intermediate bars next to the middle bar and meshing with the racks of the middle bar and the racks of adjoining outer bars, the gear on the middle bar and the racks of the intermediate bars meshing therewith being let into recesses in the under sides of said bars and located in a plane above and parallel with the plane of the gears on the adjoining intermediate bars and of the racks meshing therewith.
4. The combination with a table comprising a central support and separable top sections, of two slides each comprising a middle bar fixed to said support and provided with two oppositely facing racks, two outside bars fixed to the top sections of the table and intermediate floating bars provided with racks and slidably connected with the middle and outside bars, a gear mounted on each middle bar and meshing on opposite sides with the racks of adjoining floating bars, and gears mounted on intermediate floating bars and meshing on opposite sides with the racks of the middle bars and of adjoining outer bars, the gear of the middle bar and the racks with which it meshes being let into recesses in the under sides of the middle and intermediate bars and located in a plane above and parallel with the plane of the other gears and racks.
- 5 to the middle bar and meshing with the racks of the middle bar and the racks of adjoining outer bars, the gear on the middle bar and the racks of the intermediate bars meshing therewith being let into recesses in the under sides of said bars and located in a plane above and parallel with the plane of the gears on the adjoining intermediate bars and of the racks meshing therewith.
- 10 4. The combination with a table comprising a central support and separable top sections, of two slides each comprising a middle bar fixed to said support and provided with two oppositely facing racks, two outside bars and meshing on opposite sides with the racks of the middle bars and of adjoining outer bars, the gear of the middle bar and the racks with which it meshes being let into recesses in the under sides of the middle and intermediate bars and located in a plane above and parallel with the plane of the other gears and racks.
- 15 4. The combination with a table comprising a central support and separable top sections, of two slides each comprising a middle bar fixed to said support and provided with two oppositely facing racks, two outside bars and meshing on opposite sides with the racks of the middle bars and of adjoining outer bars, the gear of the middle bar and the racks with which it meshes being let into recesses in the under sides of the middle and intermediate bars and located in a plane above and parallel with the plane of the other gears and racks.

In witness whereof I hereto affix my signature.

SAMUEL GALERKIN.
